BAKER'S COOLING RACK

Kurt Christoffersen, Norwich, Conn., assignor to The Artistic Wire Products Co. of Conn., Incorporated, Taftville, Conn., a corporation of Connecticut

Original design application Jan. 22, 1964, Ser. No. 78,318, now Design Patent No. 201,903, dated Aug. 10, 1965. Divided and this application Apr. 27, 1965, Ser. No. 84,976

Term of patent 14 years

(Cl. D44—29)

FIG. 1

FIG. 2

FIG. 3

FIG. 4

FIG. 1 is a perspective view of a cooling rack showing my new design, wherein the foot member forms a substantially plane, closed geometric configuration with respect to the end stringer;

FIG. 2 is a top plan view thereof;

FIG. 3 is an edge elevational view;

FIG. 4 is a side elevational view of the baker's cooling rack of my new design.

The essential feature of my design resides in the provision of two base members having foot forms as shown, in combination with superposed transverse stringers, the short ends of the base members being outwardly disposed with respect to the end stringers, all as shown.

This application is a division of my earlier filed design application Serial No. 78,318, filed January 22, 1964, now Design Patent No. 201,903, dated August 10, 1965.

I claim:

The ornamental design for a baker's cooling rack, as shown and described.
